BOILER

Wilbur H. Armacost, New York, N. Y., assignor
to The Superheater Company, New York, N. Y.

Application June 6, 1934, Serial No. 729,190

11 Claims. (Cl. 122—235)

My invention relates to the art of generation of steam and aims to provide a boiler of economical construction and one having ample supply of water to the generating tubes.

5 An object of my invention also is to improve the details of arrangement of superheater boilers.

A boiler in accordance with my invention is illustrated in the accompanying drawings and 10 in order that my invention, together with its objects and advantages, may be fully and readily understood, I will now describe said illustrated boiler in detail in connection with the drawings, such illustrated boiler having been selected as an exemplification of the invention 15 from a number of possible embodiments thereof. In the drawings,

Fig. 1 is a vertical sectional elevation of a boiler in accordance with my invention.

20 Fig. 2 is a fragmentary elevation taken from the left of Fig. 1.

Fig. 3 is a fragmentary elevation taken from the right of Fig. 1.

The boiler 10 illustrated in the drawings, is of 25 the horizontal inclined water tube type having a single transverse steam and water drum 12 and two banks 14 and 16 of generating tubes, bank 14 being set above and spaced vertically from bank 16 to provide what is ordinarily known as an interdeck space 15.

30 At the lower end of bank 14 the generating tubes of such bank are connected into headers 17a and 17b. Headers 17a alternate with headers 17b in the direction parallel to the drum 12. Headers 17a are interrupted im-

35 mediately below the bank 14 whereas headers 17b are extended downwardly therefrom for a purpose which will presently appear. At the upper end of bank 14 the generating tubes are connected into headers 18 and the usual circu-

40 lators 19 are provided for conducting steam and water from the upper ends of headers 18 to the drum 12. Also, the usual downcomers 20 are provided for conducting water from the drum 12 into the upper ends of headers 17a and 17b. At the

45 lower end of the bank 16, part of the generating tubes of such bank are connected into the lower ends of the long headers 17b and the remainder of the tubes of bank 16 are connected at their lower ends into short riser headers 22. Headers 22 alternate with the lower ends of headers 17b in the direction parallel to the drum 12 and lie in the same vertical planes as headers 17a. A mud drum 24 is connected to the bottoms of all

50 the headers 17b and 22. At the upper end of

bank 16, the generating tubes of such bank are connected into headers 26 from which steam and water are conducted through the risers 28 to the upper ends of the headers 18 from which points the steam and water is delivered to drum 12 5 through the circulators 19. Water for some of the generating tubes in bank 16 is introduced into the lower ends of the tubes of such bank directly from the downcomer headers 17b. Water for the remainder of the tubes of bank 16 enters the 10 lower ends of headers 22 from the mud drum 24 which receives the water in the first place from the downcomer headers 17b.

Preferably also, the short riser headers 22 are connected into the bottoms of the headers 18 15 by generating tubes 16b. It will be seen further that boiler 10 is illustrated as being of the three-pass type, and I have found it convenient to provide Z-shaped generating tubes 18b which connect at their lower ends into the long headers 17b at points somewhat above the level of the tops of short riser headers 22. Tubes 18b cross the space 15 about at their middles and connect at their upper ends into the lower ends of headers 18. The tubes 18b can be used conveniently 20 to support the ordinary horizontal and vertical baffle 21. Tubes 18b, however, are spaced enough above the tubes of bank 16 and the tubes 16b to provide a convenient space 15a extending between tubes 16b and 18b throughout the main 25 interdeck sections of such tubes which lie the closest together and well adapted for accommodating the lower ends of superheater units 23 which ordinarily are placed in the interdeck space at one side of baffle 21. 30

Below the bank 16 is a furnace chamber 30. Ordinarily, such furnaces are rectangular and I have shown on the inner faces of the wall of such chamber a water wall composed of generating tubes 32, 32 arranged in sections, one section 40 for each vertical face of the chamber. The generating tubes 32 of the water wall section 34 on the face of chamber 30 beneath drum 12 connect at their lower ends into a header box 36 and receive water from such box. The tubes 32 of the water wall section 38 on the face of chamber 30 opposite section 34 connect at their lower ends into header box 40 so as to receive water therefrom. Water is conducted from box 36 to box 40 by bottom tubes 42 which extend across furnace chamber 30 at its lower end. Box 36 receives its water through nipples 43 from a drum 44 which is supplied by downcomers 46 and 48, downcomers 46 connecting at their upper ends 45 into the bottoms of the short headers 17a and 50 55

the upper ends of downcomers 48 connecting into the drum 24. The generating tubes 32 on the water wall sections 58, 59 on the two faces of the chamber 30 perpendicular to drum 12 also receive their water from drum 44. At their lower ends 5 the tubes 32 on such walls 58 connect into header boxes one of which is shown at 52, header boxes 52 being connected to the drum 44 by a plurality of connectors 54 which connect into the drum 44 and into the boxes 52 at spaced points along the lengths of such members.

The generating tubes 32 forming section 34 of the water wall connect at their upper ends into a header box 56 and steam and water from the header box 56 is conducted across the upper end 15 of the chamber 30 and delivered into the lower portions of headers 26 by means of generating tubes 58, 58 which lie below the bank 16. At their upper ends, the tubes 32 forming part of the water wall section 38 connect into a header box 60 and steam and water from the header box 60 are delivered into the bottoms of the headers 26 by risers 62. The generating tubes 32 forming water wall sections 50 along the sides of chamber 30 connect at their upper ends into header boxes 25 one of which is shown at 64 and steam and water from the boxes 64 are conducted upwardly by risers 66, 66 which deliver into subheaders 68 shown as lying at a level above that of the circulators 19. From the subheaders 68 steam and water is conducted to the drum 12 by connectors 10 which connect into the drum 12 and into the header 68 at spaced points along the lengths of such members.

Inasmuch as the tubes of the bank 14 are the more remote from the combustion chamber, the rate of fluid circulation through these tubes is less than through others, as in the bank 16, and less than the capacity of the feed headers 17a, 17b for the bank 14. Moreover, the downward extension of the headers 17b for feeding tubes of bank 16 (instead of connecting headers for banks 14 and 16 by conventional downcomers of smaller diameter than the headers) further increases the capacity of these headers. Consequently, the 40 excess capacity of the feed headers for the bank 14 may be availed of for feeding alternate vertical rows of tubes of bank 16 directly through the extended headers 17b and the remainder of the bank 16 from the headers 17b by way of mud drum 24 and the short riser headers 22 of the bank 16. Likewise, without substantially increasing the size of headers 17a, 17b for bank 14, the tubes 32 of the furnace wall sections are fed 45 through the downcomers 46, 48 connected, respectively, to the short headers 17a for the bank 14 and the mud drum 24 associated with the bank 16. As a result, it is possible to avoid the necessity of providing separate downcomers from water drum 12 to the lower bank 16 and to the banks of tubes 32 comprising the wall sections 34, 38, 50, 50 about the furnace chamber.

By connecting the risers 62 from drum 60 to the upper headers 26 of the bank 16 the provision of additional and long risers extending externally of the boiler proper to water drum 12 is avoided. Furthermore, the risers 62 close in the space between the wall section 38 and the upper end of bank 16 and provide a mounting for a refractory wall at this point thereby avoiding the necessity of providing a separate wall support. Likewise the connection of the upper row of tubes 16b of the bank 16 to the riser header 18 for bank 14 closes in the space between the upper end of this bank 70 and bank 16 and also provides a wall support.

In addition, this connection of tubes 16b diverts part of the load of bank 16 to the upper headers 28 for bank 14, thus relieving the riser headers 26 and providing in part for the load imposed thereon by wall sections 34 and 38.

It may be noted that the riser tubes 66 which extend between the header boxes 64 for the side wall sections 50 and the sub-headers 68 are disposed along the sides of the boiler closely adjacent the sides of the tube banks 14, 16 and exposed to the gases of combustion thus increasing the amount of heat absorbed therefrom. Thus in addition to increasing the efficiency of the boiler the absorption of a greater amount of heat from the gases of combustion, makes it 10 possible to decrease the thickness of the refractory walls and the boiler insulation.

It should also be noted that by feeding the wall sections 34, 38, 50, 50 from the headers 17a for bank 14 and the mud-drum 24 associated with bank 16 and by connecting the header boxes 56, 60 for the wall sections 34, 38 into the upper header 26 of bank 16, an amount of piping that would ordinarily be employed for downcomers and risers between these generating tubes and water drum 12 may be eliminated. Consequently, a considerable saving may be attained in the cost of downcomer and riser connections and the insulation therefor. Further, this arrangement by dispensing in great part with the maze of 20 downcomer and riser connections that ordinarily extend externally of the boiler proper between the water drum 12 and such generating tubes permits the boiler to be made more compact in construction inasmuch as most of the downcomers 25 and risers are located within the confines of the boiler proper.

The feeding of alternate vertical rows of tubes of bank 16 from the adjacent extended headers 17b and through short riser headers 22 and mud-drum 24, to which headers 22 are connected at their bottoms, eliminates downcomers between headers 22 for bank 16 and the aligned headers of bank 14 such as have been heretofore provided. This arrangement together with the interruption 40 of the aligned headers 17a for bank 14 immediately below the latter provides space intermediate the extended headers 17b and between the headers 17a, 22 through which the lower ends of the tubes of the superheater may be extended, with 45 conveniently adjacent support therefor, for connection to the inlet header of the superheater, thereby facilitating the location of this drum exteriorly of the boiler proper as is advantageous. Likewise, the upper ends of the superheater tubes may be extended between and supported adjacent the substantially vertical portions of the upper row of generating tubes 16b that are connected between headers 22 and riser header 18 so that the collecting drum of the superheater may also be located exteriorly of the boiler proper.

Another important advantage arising from this arrangement and the location of baffle 21 in the interdeck space 15 with its horizontal portion 65 spaced from bank 16 is that the lower ends of the superheater may be extended beneath the baffle 21 and exposed to the gases of combustion so that the heat absorbing surface of the superheater is increased considerably.

What I claim is:

1. A boiler having a steam and water drum, vertically spaced banks of inclined generating tubes, downcomer and riser headers connected to the ends of all the vertical rows of the upper 75

one of said banks, alternate ones of said downcomer headers being extended downwardly and connecting to alternate rows of tubes in the lower bank, relatively short riser headers at the lower end of alternate vertical rows of said lower bank, riser headers at the upper ends of the tubes of said lower bank, a mud drum connecting all the headers at the lower end of said lower bank whereby water from the through headers is supplied to alternate vertical rows of said lower bank through such mud drum to the lower ends of some of said short headers, and means, including riser nipples extending from the upper ends of the upper riser headers of said lower bank, for connecting the tubes of the lower bank to the steam and water drum.

2. A boiler as set forth in claim 1 and in which the tubes in the top row of the lower of said banks are connected into the bottoms of the headers at the upper ends of the tubes of the top one of said banks.

3. A boiler having a steam and water drum, downcomers for leading water from said drum, said downcomers including relatively long headers and relatively short headers, generating tubes connected to said headers, means for conducting steam and water from said generating tubes back to said steam and water drum, a furnace chamber below said generating tubes, water wall tubes on the inner face of said chamber, and means for supplying said water wall tubes with water comprising downcomer connections leading from the bottom of each of said short downcomer headers.

4. A boiler as set forth in claim 3 together with a mud drum connected along the lower ends of the relatively long downcomer headers, and additional downcomer connections for said water wall leading from said mud drum.

5. A water tube boiler having a pair of vertically spaced banks of inclined generating tubes, a combustion chamber beneath the lower of said banks, downcomer headers at the lower ends of the tubes of the upper of said banks, certain of said headers extending downward below the lower of said banks and acting as downcomers also to certain of the tubes of such lower bank, a mud drum connected to the lower ends of said headers having the greater downward extension, certain of said headers interrupted at points above the level of the top of said lower bank, riser headers connected to said mud drum and arranged to conduct water therefrom to the remainder of the tubes of said lower banks, water wall generating tubes on the inner face of said combustion chamber, and downcomer means for conducting water from the lower ends of said interrupted headers to the lower ends of said water wall tubes.

6. A boiler having vertically spaced banks of inclined generating tubes; downcomer headers into which said tubes are connected at their lower ends; riser headers into which said tubes are connected at their upper ends, the risers for the lower of said banks being separate and spaced vertically from the risers of the upper bank, said risers being unconnected at their adjacent ends; and a row of generating tubes extending along the upper edge of the lower bank for substantially the entire length thereof to adjacent the riser headers therefor and thence upwardly between said banks to the lower ends of the riser headers of said upper bank.

7. A boiler having a steam and water drum; banks of inclined generating tubes spaced vertically to provide an interdeck space; riser headers connected to the upper ends of the tubes of both

of said banks and to said drum; downcomer headers connected to the ends of all the vertical rows of the upper one of said banks, alternate ones of said downcomer headers extending downwardly and connecting to alternate rows of tubes in the lower bank and others of said headers terminating immediately below said upper bank; relatively short riser headers at the lower end of other vertical rows of said lower bank, the upper ends of said short riser headers being spaced from the lower ends of said other downcomer headers of said upper bank; a drum connecting all the headers at the lower end of said lower bank whereby water from said extended headers of said upper bank is supplied to alternate vertical rows of said lower bank through said drum and said short headers; and a superheater comprising tubular elements each having one end thereof projecting from said interdeck space intermediate said extended downcomer headers between said ends of said other headers for said upper bank and said short riser headers for said lower bank.

8. A boiler having a steam and water drum; upper and lower banks of inclined generating tubes spaced vertically to provide an interdeck space; downcomer headers connected to said drum and to the lower ends of alternate rows of vertical tubes in said upper and lower banks; downcomer headers connected to said drum and to the lower ends of the intermediate vertical rows of tubes in said upper bank, said headers terminating immediately below said upper bank; short riser headers connected to the lower ends of said first mentioned downcomer headers and the lower ends of the intermediate vertical rows of tubes in said lower bank, said short riser headers being spaced from the downcomer headers that are connected to the intermediate vertical rows of tubes in said upper bank; riser headers connected to said drum and to the upper ends of the tubes of said banks, the riser headers for said lower bank being separate and spaced from the riser headers of said upper bank; a row of tubes extending from headers connected to the lower end of tubes of said lower bank along the upper edge of said bank to adjacent the riser headers therefor and thence upwardly between said banks to the lower end of the riser headers for the upper bank; and a superheater comprising tubular elements each having one end thereof projecting from said interdeck space between the short risers at the lower end of said lower bank and the downcomers connected to intermediate rows of tubes of said upper bank and having their other ends projecting from said interdeck space between upwardly extending portions of said row of tubes along the upper edge of said lower bank.

9. In a boiler having a steam and water drum, and upper and lower banks of inclined generating tubes spaced vertically to provide an interdeck space in which the heat absorbing elements of a superheater are located at one side of a baffle including an upper portion extending through the upper bank and a lower portion extending along part of the lengths of the tubes of the lower bank; headers connected to the upper and lower ends of the tubes of both banks, certain of the lower headers for one bank extending beyond the end of said bank and other adjacent lower headers terminating short of the corresponding ends of said certain headers to provide passages adjacent the latter between the ends of said other headers and the corresponding headers of the other bank through which end portions of said superheater units extend for connection to a

header located exteriorly of said interdeck space; and means connecting all said headers to said steam and water drum.

10. In a boiler having a steam and water drum and upper and lower banks of inclined generating tubes spaced vertically to provide an interdeck space in which the heat absorbing elements of a superheater are located at one side of a baffle including an upper portion extending through the upper bank and a lower portion extending along part of the lengths of the tubes of the lower bank; downcomer headers connected to the lower ends of the tubes of said upper bank, certain of said headers extending also along the lower ends 10 of tubes of the lower bank and connected thereto while others of said headers terminate at a level somewhat below said upper bank and above the corresponding headers of the lower bank to provide passages adjacent said certain headers through which end portions of said superheater units project for connection to a header located exteriorly of said interdeck space; and means connecting all said headers to the steam and water drum of the boiler.
25. 11. In a boiler having a steam and water drum, and upper and lower banks of inclined generating tubes spaced vertically to provide an interdeck space in which the heat absorbing elements of a superheater are located at one side of a baf-

fle including an upper portion extending through the upper bank and a lower portion extending along part of the lengths of the tubes of the lower bank; headers connected to the upper and lower ends of the tubes of both banks, certain of the lower headers for one bank extending beyond the end of said bank and other adjacent lower headers terminating short of the corresponding ends of said certain headers to provide passages adjacent the latter between the ends of said other headers and the corresponding headers of the other bank through which end portions of said superheater units extend for connection to a header located exteriorly of said interdeck space; Z tubes each connected at one end to upper headers of said upper bank and extending along the upper and lower portions of the baffle to support the latter and having the ends thereof that extend along the lower portion of the baffle connected into said certain headers at points above the upper row of tubes of the lower bank to provide a space between said lower portion of the baffle and the said upper row of tubes for receiving the end portions of the superheater units that project through said passages for connection to said superheater header; and means connecting all said headers to the steam and water drum of the boiler.

WILBUR H. ARMACOST.
